(57) **CLAIM**

The ornamental design for a rocking chaise lounge, as shown.

DESCRIPTION

FIG. 1 is a rear quarter perspective view of the rocking chaise lounge of this invention;

FIG. 2 is an enlarged right hand side elevation of FIG. 1, the left hand side view being its mirror image;

FIG. 3 is a top view of FIG. 2;

FIG. 4 is a bottom view of FIG. 2;

FIG. 5 is a front elevation of FIG. 2; and,

FIG. 6 is a rear elevation of FIG. 2.

The fragmented crosshatch pattern shown on the seat and backrest represent fabric and is repeated throughout the areas shown.
